US00D932119S

(12) **United States Design Patent** (10) Patent No.: **US D932,119 S**
Chang (45) Date of Patent: **** Sep. 28, 2021**

(54) **CLEANER**

(71) Applicants: **Excelsior Medical Co., Ltd.**, New Taipei (TW); **Hung Hsing Electric Co., Ltd.**, Tainan (TW)

(72) Inventor: **Ming-Cheng Chang**, New Taipei (TW)

(73) Assignees: **Excelsior Medical Co., Ltd.**, New Taipei (TW); **Hung Hsing Electric Co., Ltd.**, Tainan (TW)

(**) Term: **15 Years**

(21) Appl. No.: **29/727,357**

(22) Filed: **Mar. 10, 2020**

(30) **Foreign Application Priority Data**

Sep. 10, 2019 (TW) 108305491

(51) LOC (13) Cl. **15-05**

(52) U.S. Cl.

USPC **D32/1**

(58) **Field of Classification Search**

USPC D15/122; D23/207; D24/217; D32/1
CPC A47L 11/284; B08B 3/02

See application file for complete search history.

CLAIM

The ornamental design for a cleaner, as shown and described.

DESCRIPTION

FIG. 1 is a 1st perspective view of cleaner, showing my new design;

FIG. 2 is a 2nd perspective view thereof;

FIG. 3 is a front elevational view thereof;

FIG. 4 is a rear elevational view thereof;

FIG. 5 is a left side elevational view thereof;

FIG. 6 is a right elevational view thereof;

FIG. 7 is a top elevational view thereof;

FIG. 8 is a bottom elevational view thereof;

FIG. 9 is a reference view during usage;

FIG. 10 is a reference view during usage; and,

FIG. 11 is a sectional view of FIG. 5.

The broken line showing of a display screen forms no part of the claimed design.

1 Claim, 11 Drawing Sheets
